UNITED STATES PATENT OFFICE

JACOB TELLER, OF CHICAGO, ILLINOIS, ASSIGNOR TO TELLER CORPORATION, OF CHATANOOGA, TENNESSEE, A CORPORATION OF TENNESSEE

DESIGN FOR A COMBINATION CLOSED-TOP GAS OR ELECTRIC COOK RANGE AND CABINET AND REFRIGERATOR UNIT

Application filed October 29, 1930. Serial No. 37,426. Term of patent 7 years.

To all whom it may concern.

Be it known that I, JACOB TELLER, a citizen of the United States, residing at Chicago, in the county of Cook and State of Illinois, have invented a new, original, and ornamental Design for a Combination Closed-Top Gas or Electric Cook Range and Cabinet and Refrigerator Unit, of which the following is a specification, reference being had to the accompanying drawing, forming a part thereof.

Figure 1 is a front perspective of the combination cook and refrigerator unit with the cover closed, and

Figure 2 is a similar view with the cover raised to provide a shelf and hood.

I claim:

The ornamental design for a combination closed top gas or electric cook range and cabinet and refrigerator unit as shown.

JACOB TELLER.
